UNITED STATES PATENT OFFICE.

RUSSELL R. KEESLING, OF SAN JOSE, CALIFORNIA.

COLLAPSIBLE BED.

Application filed October 23, 1924. Serial No. 745,477.

It is one object of my invention to provide a collapsible bed that can be readily mounted in the coupé type of closed motor cars without alteration of the car body, and 5 readily adjustable for use without material alteration of the car parts.

It is another object of the invention to provide a collapsible framework constructed to cooperate with a portion of the car to 10 form a bed support.

It is also an object of the invention to provide a structure of the character indicated that will be simple in form and construction, economical to manufacture, and highly 15 efficient in its practical application.

In the drawing:—

Figure 1 is a diagrammatical illustration of a portion of a coupé body with my improved bed installed therein.

20 Figure 2 is a plan view of the collapsible framework supporting a portion of the bed.

Referring more particularly to the drawing, I show at 1 the outline of a coupé body with the framework 3 having two 25 independent cushion sections 2—2 disposed side by side thereon to constitute a seat.

There are certain features in the construction of the type of coupé for which this structure is designed that renders the 30 construction hereinafter set forth highly practical.

For instance, the space 4 is such that the seat cushions 2 may be removed from frame 3 and placed in superposed relation in said 35 space as shown in Figure 1, thereby forming a support for the head of a mattress as 5 on substantially the same level as the top of frame 3.

Furthermore, the space 6 is substantially 40 the same in height as the back 7 of the seat, and a shelf-like portion 8 is provided to the rear of the seat back 7 so that when so desired the back 7 may be quickly slid up on to shelf 8 as shown. This is a simple operation 45 to perform because the back 7 is normally secured to frame 3 only by lugs as 9 screwed thereto, but in fitting the car with a bed these lugs may be permanently detached from frame 3 since the cushions 50 2 securely hold the back 7 in place.

Finally, when the seat back 7 is raised to shelf 8 as shown an opening 10 is left between body 1 and frame 3, providing an unobstructed space somewhat over six feet 85 long extending from the front to the rear of the car body.

While the framework 3 and cushions 2 (when arranged as shown) will support the forward part of a mattress it is necessary to provide suitable means for supporting 60 the foot portions thereof.

To accomplish this result I provide a three leaf collapsible bed frame as follows. An oblong frame 11 of suitable proportions is hinged as at 12 to the rear upper corner 65 of framework 3 and is normally supported flush with the top thereof by legs as 13, the legs consisting simply of a pipe extending lengthwise through frame 11 and turned at right angles thereto at each end and freely 70 pivoted therein.

The second frame 14 is hinged to the upper rear edge of frame 11 and similarly provided with legs 15.

A third frame is hinged to the lower rear 75 edge of frame 14 and provided with legs 17.

To collapse this bed frame, each pair of legs is turned up into parallel relation to the plane of the leaf in which they are mounted and then the leaves are folded 80 back against the rear vertical surface of framework 3 as shown in dotted lines at 18.

When the back 7 and cushions 2 are arranged as shown and the collapsible bed frame extended it is only necessary to lay 85 a mattress over the bed frame, framework 3 and cushions 2 to form a comfortable bed.

When the bed is not desired it is only necessary to fold the mattress 5 back into the rear compartment 19 or to fold the 90 collapsible bed frame as described and also fold the four-fold mattress 5 and store it against the folded bed-frame as shown in dotted lines at 20.

In the opening 10 I arrange a rod 21 95 crosswise of the car body and on pivots as 22. When it is desired to put the bed away the coverings used may be rolled up on rod 21 directly from the bed. Likewise in preparing the bed for use they may be unrolled directly upon the mattress in their proper order. This method of storing the bed clothes also keeps them perfectly clean when not in use.

It is to be understood, of course, that 105 while I have herein shown and described one specific embodiment of my invention, changes in form, construction and method of application may be made within the scope 110 of the appended claims.

I claim:—

1. In combination with a motor car hav-

- ing two-part removable seat cushions and a removable back cushion and a space between the seat frame and the forward portion of the car body substantially filled by said seat
5 cushions when placed therein one upon the other, of a foldable mattress supported at its forward portion by the seat frame and said seat cushions when placed in said space, and means for supporting the rear portion
10 of said mattress said means comprising a collapsible frame pivotally mounted at the rear upper edge of the seat frame and proportioned to fold flat against the rear vertical side of said seat frame.
15 2. In combination with a motor car hav-

ing two-part removable seat cushions and a removable back cushion and a space between the seat frame and the forward portion of the car body substantially filled by said seat cushions when placed therein one 20 upon the other, of a foldable mattress supported at its forward portion by the seat frame and said seat cushions when placed in said space, and means for supporting the rear portion of said mattress, said means 25 comprising a collapsible frame mounted at the rear of the seat frame and proportioned to fold flat against the rear vertical side of said seat frame.

RUSSELL R. KEESLING.
